(57) **CLAIM**

We claim the ornamental design of a gun body, as shown and described.

DESCRIPTION

FIG. 1 is an upper perspective view of a gun body showing our new design;

FIG. 2 is lower perspective view of the gun body of FIG. 1;
FIG. 3 is a front elevated view of the gun body of FIG. 1;
FIG. 4 is rear elevated view of the gun body of FIG. 1;
FIG. 5 is a left side elevated view of the gun body of FIG. 1;

FIG. 6 is a right side elevated view of the gun body of FIG. 1;

FIG. 7 is a top plan view of the gun body of FIG. 1;
FIG. 8 is a bottom plan view of the gun body of FIG. 1; and,
FIG. 9 is a cross-section view of the gun body of FIG. 7
along line 9-9.

The broken lines consisting of dashes show an environment
that forms no part of the claimed design.

1 Claim, 8 Drawing Sheets

Related U.S. Application Data

of application No. 16/455,816, filed on Jun. 28, 2019, now Pat. No. 10,844,696, which is a continuation of application No. 16/272,326, filed on Feb. 11, 2019, now Pat. No. 10,458,213.
